UNITED STATES PATENT OFFICE.

CHARLES B. FOSTER, OF INDIANAPOLIS, INDIANA.

CONCRETE CONSTRUCTION.

Application filed September 25, 1920. Serial No. 412,723.

To all whom it may concern:

Be it known that I, CHARLES B. FOSTER, a citizen of the United States, residing at Indianapolis, in the county of Marion and

5 State of Indiana, have invented new and useful Improvements in Concrete Constructions, of which the following is a specification.

This invention relates to a new concrete 10 construction and method of making the same, which construction may be a train-shed, a loading platform, a portion of a building, or other desired construction of a similar nature.

15 Among the objects of my invention are to produce a strong monolithic concrete unit slab and supporting means, to produce a strong monolithic concrete arch slab, to produce a concrete truss slab, to provide a new 20 and improved method of forming concrete structures, and such further objects, advantages and capabilities as will later more fully appear.

25 My invention further resides in the combination, construction, and arrangement of parts illustrated in the accompanying drawings, and in the parts of my method herein disclosed, and while I have shown in the annexed drawings, preferred embodiments, I 30 desire the same to be understood as illustrative only, and not as limiting my invention.

35 In the accompanying drawings illustrating my said invention, Fig. 1 is a diagrammatic plan of an arch slab according to my invention and illustrating the arrangement of parts when the supporting members are placed at the corners of a slab, the concrete being broken away from the top to expose 40 the reinforcement; Fig. 2 is a similar view but showing the slab supported by a centrally arranged post, and with the thick portion at the center; Fig. 3 is a broken plan view showing the arrangement of truss 45 work and flooring used in the making of my new construction; Fig. 4 is a vertical section through the structure shown in Fig. 3, substantially along the plane indicated by line 4—4, Fig. 3; Fig. 5 is a horizontal section, looking upwardly, in a construction 50 such as shown in Fig. 6; Fig. 6 is a longitudinal section, substantially through the centers of the columns shown in Fig. 5; Fig. 7 is a broken elevation of a portion of a 55 loading platform or train-shed, to illus-

trate the application of my invention to such a structure; and Fig. 8 is a cross-section through a structure such as illustrated in Fig. 7.

Referring more in detail to the annexed drawings, numeral 1 indicates the supporting columns or posts and 2 a supported member integral therewith. This supported member may constitute either a roof for a 60 platform or floor below, may be a floor in itself, or may constitute both a floor for one space and a roof for another. It extends laterally away from the supporting column, and consists of two parts 3 and 4, the first 65 of which gradually diminishes in thickness away from the column to form cantilever portions, while the part 4 is of substantially uniform thickness throughout its entire extent. The supported structure or slab 2 70 may have its connection with the column 1 reinforced by a collar 5 tapering upwardly and outwardly. Where the structure is formed as a single monolithic slab and supporting column, as in Fig. 2, the portion 4 75 surrounds the outside thereof. Where, 80 however, an arch slab construction is used, supported upon a plurality of columns, as in Fig. 1, the part 4 connects the edges of portions having a decreasing thickness. In Fig. 1 the parts of uniform thickness are 85 shown between the dotted lines, while the parts decreasing in thickness are shown at the corners within the dotted lines. In Fig. 2 the parts of uniform thickness form 90 a peripheral or perimetrical edging for the other portions 3 which are connected at their peripheries or margins by the portion 4. It will of course be understood that the portions 3 surrounding a column may, 95 if desired, be made of a standard size, and have their edges connected together by narrower or wider strips 4 in order to vary the size of the structure as a whole.

In thus varying the size of strips 4 it may 100 even result that they will be entirely dispensed with. In this connection it should also be noted that the columns may be rectangular, hexagonal or other form, in cross-section, equally as well as circular and that the portions 3 may be inverted frusto-conical 105 as well as inverted frusto-pyramidal. When the parts are made in this form, the under surface of part 3 will have the same pitch along all lines radiating from the columns and the parts 4 have their portions, inter- 110

mediate adjacent parts 3, more or less pointed depending upon whether or not the adjacent inclined surfaces contact at their outer edges or are some distance apart. In 5 any of these forms the collar 5 may be used or omitted as is deemed necessary or desirable.

Use is made of reinforcing rods 6 extending substantially at right angles to each 10 other and embedded in the concrete to assist in supporting the same. These rods are substantially straight throughout their 15 lengths, and are nearest together in the vicinity of the columns where the strain is greatest and farther apart at points more remote from the columns. The arrangement of these reinforcing rods is shown most clearly in Figs. 1 and 2, in which are also shown diagonally arranged reinforcing 20 rods 7.

In Figs. 3 and 4 is shown the arrangement of the centering used in the formation of one of the forms of my new construction. It 25 will be apparent from these figures that a system of uprights 8 are connected at their upper ends by beams 9, 10, 11, 12 and 13, on which rest the floor sections 16 and 17, for forming respectively the portion of uniform thickness and the portion increasing 30 gradually in thickness towards the columns. Extending downwardly from the central portion of the floor is a frusto-conical member by means of which is formed the collar 5. Extending downwardly from the lower 35 end of this is a substantially cylindrical member 19 by means of which the column is formed. It will therefore be seen that if plastic concrete material is poured into the frusto-conical member 18, the same will run 40 downwardly and fill the tubular member 19, and when this is full if more plastic material is added, member 18 will be filled, and finally portions 3 and 4 will be formed, the final 45 result being a monolithic structure so shaped as to support quite considerable loads, and yet with all excess material omitted whereby the cost is reduced to a minimum. It is of course understood that before the entire 50 concrete mass is formed the reinforcing rods 6 and 7 are placed in position so as to be thoroughly and firmly imbedded in the concrete.

The formation of the construction shown in Fig. 3, when same is to be used for the 55 making of any of the shapes referred to above will be obvious and need not be described.

It will be seen from the above that the 60 reinforcing rods, placed near the upper surfaces of the slabs, will resist any tendency for the outer portions thereof to sag, since it will be necessary if they do sag for the rods to be stretched or the concrete in the under part of parts 3 and part 4 to be compressed. In other words, since steel is

strongest under tension and concrete under compression, these parts are so arranged as to give the maximum strength for the amount of material used, which can be varied according to the amount of load to be supported. 70

The solid lines in Fig. 5 indicate the lines along which the direction of slope changes. The circles surrounding the columns 1 also indicate changes in slope, which will be 75 evident upon a comparison of Figures 5 and 6.

The loading platform shown in Figs. 7 and 8 employs the same principle of arch slab construction as that described above, 80 and it is therefore thought unnecessary to describe this further, other than to refer to the slope of the upper surface of the cover toward the drain pipes 20 and the casing of the columns 1 by protecting members 21. 85

It is of course understood that the specific description of structure and method set forth above may be departed from without departing from the spirit of my invention, as set forth in this specification and the appended claims. 90

Having now described my invention, I claim:

1. In a concrete construction, a column, a slab integral therewith, and having a collar at the junction of said column and slab, said collar tapering downwardly and inwardly toward the column to form a reinforcement for the junction, said slab tapering laterally from the column so as to have a decreasing thickness in all directions from the column. 95

2. In a concrete construction, a column, a slab integral therewith, and having a collar at the junction of said column and slab, said collar tapering downwardly and inwardly toward the column to form a reinforcement for the junction, said slab tapering laterally from the column so as to have a decreasing thickness in all directions from the 100 column and means provided with suitable reinforcing rods to strengthen the structure. 105

3. In a concrete construction, a plurality of columns, substantially rectangular slabs of concrete surrounding and integral with the columns, and having their adjacent edges integrally united by concrete sections of substantially uniform thickness, said slabs decreasing in thickness in any direction away from the columns, to their junction with the connecting sections the opposite edges of the connecting sections being substantially parallel. 115

4. In a concrete construction, a plurality of columns, slabs of concrete surrounding and integral with the columns, and having their adjacent edges integrally united by concrete sections of substantially uniform thickness and width, said slabs decreasing in thickness in any direction away from the 120 125 130

columns to their junction with the connecting section, said concrete being provided in its upper portion with suitable reinforcing rods extending longitudinally and laterally.

5. In a concrete construction, a plurality of columns, a slab of concrete integral with each of the columns, and decreasing in thickness away from the column, the adjacent edges of adjacent slabs being integrally connected, and metallic reenforcing rods extending longitudinally and transversely of the structure and diagonally thereof to connect alternately arranged columns.

6. In a concrete construction, a plurality of columns arranged in the form of adjacent rectangles, a slab of concrete integral with each of the columns and decreasing in thickness toward points more remote from the columns along any line radiating therefrom, the adjacent edges of the slabs being integrally connected, said columns being provided with integral collars at the points of junction of the slabs and columns, said collars tapering downwardly and inwardly toward

25 the columns.

7. In a concrete construction, a plurality of columns, arranged in rectangular formation, a concrete slab integral with each column, said slabs tapering laterally away from each column and being integrally united at their adjacent edges, so as to form an arch

extending from each column to each of its adjacent columns.

8. In a concrete construction, a plurality of columns, arranged in rectangular formation, a concrete slab integral with each column, said slabs tapering laterally away from each column and being integrally united at their adjacent edges by parallel sided slabs of substantially uniform thickness formed simultaneously with the first named slabs so as to form an arch extending from each column to each adjacent column.

9. In a concrete construction, a plurality of columns arranged in the form of a rectangle, a slab of concrete integral with each column and decreasing in thickness from the columns toward a central area between adjacent columns, said concrete being provided with truss rods to act in conjunction therewith to form a trussed arch.

10. In a concrete construction a column, and a slab integral therewith, said slab tapering laterally from the column so as to be of decreasing thickness in all directions leading from the column, thereby providing a cantilever cross section which comprises approximately the entire slab.

In witness whereof, I hereunto subscribe my name to this specification.

CHARLES B. FOSTER.
